UNITED STATES PATENT OFFICE.

GEORGE B. GOFF, OF JOHNSTOWN, PENNSYLVANIA.

EXPANSION BOLT AND PLUG.

1,202,704.

Specification of Letters Patent. Patented Oct. 24, 1916.

Application filed August 23, 1916. Serial No. 116,465.

To all whom it may concern:

Be it known that I, GEORGE B. GOFF, a citizen of the United States, residing at Johnstown, in the county of Cambria, State of Pennsylvania, have invented certain new and useful Improvements in Expansion Bolts and Plugs; and I do hereby declare the following to be a full, clear, and exact description of the invention, such as will enable others skilled in the art to which it appertains to make and use the same.

This invention relates to expansion devices and has special reference to an expansion bolt and plug for use in connection with tubular boilers.

It is a well recognized fact among the users of tubular boilers that such boilers frequently leak by reason of their tubes giving away or the connections between the tube and tube sheet becoming loose. In the first instance, it is necessary to replace the tube but at times it is inconvenient to replace the tubes on account of the boiler being in service so that such replacements are preferably put off.

One important object of the invention is to provide an improved expansion bolt and plug for use in connection with such tubes so that both ends of the leaky tube may be closed if desired, thus enabling the boiler to continue in use until a convenient time is found for repairs.

In the second instance, where the leak occurs around the connection between the tube and the flue sheet it is necessary to reexpand the tube at this point and probably to reheat such tube. This also requires shutting down of the boiler and a second important object of the invention is to provide means which will avoid this shutting down at inconvenient times by providing an expansion bolt and plug, which plug will fit in the mouth of the tube and by reason of its tapering formation force the wall of the tube firmly into engagement with the opening in the tube or flue sheet so that no leakage can take place.

With the above and other objects in view, as will be hereinafter apparent the invention consists in general of certain novel details of construction and combinations of parts hereinafter fully described, illustrated in the accompanying drawings, and specifically claimed.

In the accompanying drawings, like characters of reference indicate like parts in the several views, and Figure 1 is a section

through a portion of a flue or tube sheet and a boiler tube or flue showing the device applied thereto. Fig. 2 is a longitudinal section through the device. Fig. 3 is a section on the line 3—3 of Fig. 1. Fig. 4 is a detail perspective of one of the pivoted members of the expansion bolt.

In carrying out the objects of this invention there is provided a body 10 having a threaded opening 11 extending centrally therethrough. At diametrically opposite points this body is also provided with recesses 12 and through these recesses pass pivot pins 13 whereto are pivoted the reduced ends 14 of expansion members 15 having their confronting faces formed with grooves 16 angularly disposed with reference to each other.

At 17 is a rod which has its inner end threaded as at 18 and this threaded end is screwed through the opening 11. Formed on or secured to this rod is a frusto-conical portion 19 which fits between the members 15 in the grooves 16. The rod extends outwardly from this portion 19 and has its outer end also threaded as shown at 20. On this threaded outer end is slidably mounted a frusto-conical plug 21 which is of such size as to fit closely in the mouth of a flue such as is indicated at A so that when the plug is forced into the mouth the wall of the flue will be spread and fit closely in the flue opening of a flue sheet B. Resting against the outer end of the plug 21 is an asbestos washer 22 which is stopped by a metal washer 23 against which engages the inner face of a nut 24.

In order to prevent any movement of the expansion member each of the members 15 is provided with spaced ribs 25 having sharpened biting edges as indicated at 26, these biting edges engaging the inner surface of the wall of the flue A when in position.

In the operation of the device the expansion member or inner end is placed within the tube and the rod 17 rotated so that the portion 19 is forced between the members 15. This causes these members to spread apart and thus the edges 26 will bite into the inner face of the wall of the flue. When these edges are engaged with the flue in this way the plug 21 is placed on the member 17 together with the washers 22 and 23 and then the nut 24 is screwed up on the member 17 so that the plug is forced

tightly into place. By reason of the fact that the threads on the ends 18 and 20 of the member 17 are of like hand there will be no tendency on the part of the portion 5 19 to move outward when the nut 24 is screwed up but on the contrary, the tendency will be to move inward, if at all. It will be obvious that under this construction, as shown in Fig. 1, the mouth of the flue 10 will be forced firmly outward so that the flue wall will engage the opening in the flue sheet. It will also be obvious that if the flue leaks between its ends it is merely necessary to apply one of these devices to 15 each end of the leaking flue whereupon the leakage from the water space of the boiler into the flue will simply accumulate in the latter without working any injury other than reducing the heating surface of the 20 boiler slightly. Thus, whenever the flue leaks, either intermediate its ends, or at its connection with a flue sheet the device may be applied without shutting down the boiler so that the latter can be continued in 25 operation until a convenient time for shutting down occurs, when permanent repairs will be effected.

There has thus been provided a simple and efficient device of the kind described 30 and for the purpose specified.

It is obvious that many minor changes may be made in the form and construction of the invention without departing from the material principles thereof. It is not therefore desired to confine the invention to the 35 exact form herein shown and described but it is wished to include all such as properly come within the scope claimed.

Having thus described the invention, 40 what is claimed as new, is:—

1. In a device of the kind described, a body having a threaded opening, a pair of members hinged to the body and having angularly disposed confronting faces, a rod

having one end threaded and screwed into 45 said opening and having a frusto-conical portion fitting between said confronting faces, and oppositely disposed arcuate ribs formed on the free ends of the pivoted members and provided with sharpened biting edges engageable with the inside of a flue. 50

2. In a device of the kind described, a body having a threaded opening, a pair of members hinged to the body and having angularly disposed confronting faces, a rod 55 having one end threaded and screwed into said opening and having a frusto-conical portion fitting between said confronting faces, oppositely disposed arcuate ribs formed on the free ends of the pivoted members and provided with sharpened biting edges engageable with the inside of a flue, a plug mounted on the remaining end of the rod and means to force the plug 60 toward said body. 65

3. In a device of the kind described, a body having a threaded opening, a pair of members hinged to the body and having angularly disposed confronting faces, a rod 70 having one end threaded and screwed into said opening and having a frusto-conical portion fitting between said confronting faces, oppositely disposed arcuate ribs formed on the free ends of the pivoted members and provided with sharpened 75 biting edges engageable with the inside of a flue, the remaining end of the rod being also threaded with the thread of the same hand as first thread, a tapered plug slidably mounted on said last-mentioned end, and 80 a nut screwed onto said last-mentioned end and forcing said plug inwardly.

In testimony whereof, I affix my signature in the presence of two witnesses.

GEORGE B. GOFF.
